RAILWAY SIGNALING

George R. Pflasterer, Swissvale, Pa., assignor to
The Union Switch & Signal Company, Swiss-
vale, Pa., a corporation of Pennsylvania

Application December 5, 1936, Serial No. 114,399

12 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding 10 aspect of the associated wayside signal whereby there is produced a three-block, four-indication system of signaling.

The present invention is an improvement on the apparatus disclosed and claimed in United 15 States Patent No. 2,107,678 to Howard A. Thompson, issued February 8, 1938, as well as the apparatus disclosed and claimed in United States Patent No. 2,107,679 to Ralph R. Kemmerer, issued February 8, 1938.

20 I will describe one form of apparatus embodying my invention, and will then point out the novel features thereof in claims.

In the accompanying drawings, Figs. 1A and 1B are diagrammatic views which when placed 25 end to end in the order named illustrate one form of apparatus embodying my invention.

Similar reference characters refer to similar parts in each view.

Referring to the drawings, the reference characters 1 and 2 designate the rails of a stretch of railway track along which traffic normally moves in the direction indicated by the arrows. These rails are divided by insulated joints 3 into a plurality of track sections W—X, X—Y, and Y—Z.

35 As here shown, each track section is divided by insulated joints 3 into at least two subsections 1T, 2T, 3T, 4T, etc. Each subsection is provided with a track circuit which includes a track battery 4 connected across the rails at one end of the subsection and a track relay, designated by the reference character TR with a prefix the same as the numerical prefix in the reference character of the associated subsection, connected across the rails at the other end of the subsection.

45 To govern the passage of trains through the stretch of railway, a wayside signal designated by a suitable distinguishing reference character, is provided for each track section. Each of these signals includes an upper indication unit U and 50 a lower indication unit L. These units may take any one of several forms of signal mechanism such as semaphore, color light, searchlight, or position light. As here shown, each upper unit U is a semaphore arm capable of assuming a horizontal or "stop" position, a 45° or "caution" position, and a vertical or "proceed" position; and each lower unit L is a semaphore arm capable of assuming a horizontal or vertical position but not a 45° position.

55 60 For controlling the associated signal, each sec-

tion is provided with a polarized signal control relay and a neutral signal control relay designated by the reference characters HD and J, respectively, each with a prefix the same as the reference character of the associated signal.

5 For controlling the associated relay J, each section is provided with a flasher relay and an auxiliary relay designated by the reference characters F and A, respectively, each with a prefix the same as the reference character of the associated signal. As will be explained more in detail hereinafter, the relays F and A cooperate to control the associated relay J in such a manner that such relay J can be energized only if relay F is energized. As here shown, the relays F are of the flasher type having a definite operating voltage range, that is, the relays F will not operate unless the voltage supplied thereto is within predetermined maximum and minimum values. A relay of this type is described and claimed in an application for United States Letters Patent Serial No. 40,115, filed September 11, 1935, by Thomas J. O'Meara and Benjamin Mishelevich, for Electrical relays.

20 For controlling the associated relays HD and F, each section is provided with a pair of conductors each of which extends to the signal next in advance and each of which includes a front contact of each of the associated track relays.

25 Each section is provided with a source of energy (not shown) including a low voltage positive terminal, a high positive voltage terminal, and a common return terminal designated by the reference characters BL, BH, and C, respectively.

30 Each relay HD is connected to the associated pair of conductors by a resistor 11 and each relay F is connected to the associated pair of conductors through a front neutral contact and a reverse polar contact of the associated relay HD. A shunt path is provided around each resistor 11 which includes a back contact 12 of the associated relay J. As will be explained more in detail hereinafter, the pair of conductors for each section is at times supplied with energy of a relatively low value in the normal direction or in the reverse direction and at other times is supplied with energy of a relatively high value in the reverse direction. The pickup value of the relays HD is such that these relays will become picked up upon receiving energy of either value whereas the pickup value of the relays F which control the relays J is such that these relays will become picked up only upon receiving energy of the higher value. The relays F can, therefore, be picked up only when the associated relay HD is energized in the reverse direction and when the relays F are energized so that the associated relay J is energized, the resistors 11 are effective to limit the current flowing in the associated relay HD.

The relays HD and J control the magnitude and direction of the energy supplied to the line conductors for the section next in the rear.

The relays HD and J control the upper unit 5 U and the lower unit L of the associated signal in the following manner: When relay HD is deenergized (see signal 10), both semaphore arms U and L are deenergized so that signal 10 is displaying both its semaphore arms in the horizontal position to indicate "stop". When only 10 the relay HD is energized in the reverse direction (see signal 9), a caution circuit for the semaphore arm U of that signal is closed over a path which passes from terminal BL over front contact 13 of relay 9HD and semaphore arm U to terminal C. Semaphore arm U of signal 9, therefore, is in the caution position to indicate "approach next signal prepared to stop". When relay HD is energized in the reverse direction and relay J also is energized (see signal 8), the caution circuit for semaphore arm U remains closed over front contact 14 of relay 8HD and a circuit is established for the semaphore arm of the lower unit L of that 25 signal. This latter circuit passes from terminal B over front contact 14 of relay 8HD, reverse polar contact 15-16 of relay 8HD, front contact 17 of relay 8J, and semaphore arm L to terminal C. Signal 8, therefore, is displaying 30 its upper semaphore arm U in the caution position and its lower semaphore arm L in the vertical position to indicate "approach next signal at medium speed". When relay HD is energized in the normal direction (see signal 7), the caution 35 circuit for the upper semaphore arm U will remain closed over front contact 18 of relay 7HD and a proceed circuit for the semaphore arm U will be closed over a path which passes from terminal B over front contact 18 of relay 7HD, normal polar contact 19-20 of relay 7HD, and semaphore arm U to terminal C. Signal 7 is, therefore, displaying its upper semaphore arm in the vertical position to indicate "proceed at normal speed". I shall conveniently term the 40 four aspects of the signals, "stop", "approach", "approach medium", and "proceed", respectively.

As here shown, a train K is indicated diagrammatically in the section immediately to the right of location Z so that the signal 10 and associated 50 relays are all deenergized.

When signal 10 and associated apparatus is in this condition, relay 9HD is energized in the reverse direction by energy of a relatively low value over a circuit which passes from terminal 55 BL at signal 10 through back point of contact 25 of relay 10HD, front contact 26 of relay 6TR, front contact 27 of relay 5TR, back contact 12 of relay 9J, relay 9HD, front contact 28 of relay 5TR, front contact 29 of relay 6TR, and back point of contact 30 of relay 10HD to terminal C.

When relay 9HD only is energized in the reverse direction, both relay 8HD and relay 8F are energized in the reverse direction by energy 60 of relatively high value. The circuit for relay 8HD may be traced over a path which passes from terminal BH at signal 9 through back point of contact 31 of relay 9J, reverse polar contact 32-33 of relay 9HD, front contact 34 of relay 9HD, front contact 35 of relay 4TR, front contact 36 of relay 3TR, resistor 11, relay 13HD, front contact 37 of relay 3TR, front contact 38 of relay 4TR, front point of contact 39 of relay 9HD, reverse polar contact 40-41 of relay 9HD, and back point of contact 42 of relay 9J to ter-

5 minal C. The circuit for relay 8F may be traced over the same path as just traced for relay 8HD except including front contact 43 and reverse polar contact 44-45 of relay 8HD instead of resistor 11 and relay 8HD.

When relay 8F is energized, movable contact 46 is caused to alternate between engagement with fixed contacts 47 and 48 so that contacts 46-47 and 46-48 are alternately closed. The closing of contact 46-48 energizes relay 8A and the closing of contact 46-47 energizes relay 8J provided front contact 49 of relay 8A is closed. The slow releasing feature of relay 8A will insure that front contact 49 will remain closed during the open circuit periods and the slow releasing feature of relay 8J will insure that this relay also will remain picked up during open circuit periods.

When relay 8HD is energized in the reverse direction and relay 8J also is energized, relay 20 7HD is energized in the normal direction by energy of relatively low value over a path which passes from terminal BL at signal 8 through front point of contact 50 of relay 8J, normal polar contact 51-52 of relay 8HD, front point 25 of contact 53 of relay 8HD, front contact 54 of relay 2TR, front contact 55 of relay 1TR, relay 7HD, back contact 12 of relay 7J, front contact 56 of relay 1TR, front contact 57 of relay 2TR, front point of contact 58 of relay 8HD, reverse 30 polar contact 59-60 of relay 8HD, and front point of contact 61 of relay 8J to terminal C.

When relay 7HD is energized in the normal direction, the line conductors for the section next in rear of location W are supplied with 35 energy of relatively low value in the normal direction over front points of contacts 62 and 63 of relay 7HD and normal polar contacts 64-65 and 66-67 of relay 7HD so that the signal (not shown) associated with such conductors will be 40 displaying the normal proceed indication.

The resistors 11, connected in series with the relays HD when the high voltage is supplied to the associated line circuit, are of such value that the normal current flowing in such relays is just sufficient to hold the relays picked up. The relays HD, therefore, will be certain to become released when the energization of the associated line conductors is changed from the high value to the low value. The shunt path 50 including back contact 12 of the associated relay J is provided around the corresponding resistor 11 in order that the relay HD will receive sufficient energy for pickup.

As hereinbefore pointed out the relays J will 55 respond only if energized with current of the high value and then only if the value of such current is within certain maximum and minimum limits. One purpose of a relay of this type is to prevent the signal controlled thereby from 60 assuming a false proceed condition in the event the relay should become energized from a foreign current source of excessively high value. For example, if the line conductors for section 65 Y-Z should become accidentally energized from a foreign current source of a value higher than the maximum limit of relay 9F, signal 9 would not change to the less restrictive "approach medium" indication but instead would continue to indicate the more restrictive "approach" indication. In other words, the safety factor of the system is enhanced because a foreign current in the signal line circuits must be within certain maximum and minimum limits in order 70 to cause the relays F to respond thereto.

The retained neutral characteristic of the relays HD is provided to avoid tumble-down of the signal circuits to the rear during pole changing periods. For example, when the train K vacates the section immediately to the right of location Z so that the direction of energization of relay 8HD is changed from the reverse direction to the normal direction to cause signal 8 to display the normal proceed indication, front contacts 53 and 10 58 of relay 8HD do not become opened so that energization of the line circuit for section W—X is opened only during the time polar contacts 51 and 59 of relay 8HD are moving between their reverse position and normal position. This momentary interruption is of such short duration that the relay 7HD will not become released so that tumble-down of the line circuits to the rear is avoided.

Although I have herein shown and described 20 only one form of apparatus embodying my invention, it is understood that various changes and modifications may be made therein within the scope of the appended claims without departing from the spirit and scope of my invention.

25 Having thus described my invention, what I claim is:

1. In combination, a section of railway track, a pair of conductors for said section, means for supplying said pair of conductors with energy 30 of a particular magnitude and direction or with energy of a higher magnitude in the same direction or with energy of said particular magnitude but in the other direction in accordance with traffic conditions in advance of said section, a polarized relay responsive to energy of either magnitude receiving current from said conductors, another relay responsive only if said energy of said higher magnitude is within certain predetermined maximum and minimum values also receiving current from said pair of conductors, and traffic governing means for said section governed by said two relays.

2. In combination, a section of railway track, a pair of conductors for said section, means for 45 supplying said pair of conductors with energy of a particular magnitude and direction or with energy of a higher magnitude in the same direction or with energy of said particular magnitude but in the other direction in accordance with traffic conditions in advance of said section, a polarized relay responsive to energy of either magnitude receiving current from said conductors, another relay responsive only if said energy of said higher magnitude is within certain predetermined maximum and minimum values also receiving current 50 from said pair of conductors, a signal for said section, and means governed by said two relays for causing said signal to display one indication when only said polarized relay is energized in said particular direction or another indication when both said relays are energized or still another indication when only said polarized relay is energized in said other direction.

3. In combination, a section of railway track, 65 a pair of conductors for said section, means for supplying said pair of conductors with energy of a relatively low value in the reverse direction or with energy of a relatively high value in the normal direction or with energy of said relatively low value in the normal direction in accordance with traffic conditions in advance of said section, a polarized relay responsive to energy of either value receiving current from said pair of conductors, a neutral relay which becomes 70 picked up only if said energy in said reverse direction

is within predetermined maximum and minimum values, a signal for said section, and means governed by said two relays for causing said signal to indicate "approach" when said polarized relay only is energized in the reverse direction or to indicate "approach medium" when said polarized relay is energized in the reverse direction and said neutral relay is also energized or to indicate "proceed" when said polarized relay is energized in the normal direction.

4. In combination, a section of railway track, a pair of conductors for said section, means for supplying said pair of conductors with energy of a relatively low value in the reverse direction or with energy of a relatively high value in the reverse direction or with energy of said relatively low value in the normal direction in accordance with traffic conditions in advance of said section, a polarized relay responsive to energy of either value receiving current from said pair of conductors, a neutral relay, means also receiving current from said pair of conductors effective to pick up said neutral relay effective only if the energy of said high value is in the reverse direction and is within certain predetermined maximum and minimum values, a signal for said section comprising a first indication unit and a second indication unit, said first indication unit being a semaphore arm capable of assuming a stop and a caution as well as a proceed position and said second indication unit being a semaphore arm capable of assuming a proceed and a stop position, a caution circuit for the semaphore arm of the first unit including a front neutral contact of said polarized relay, a proceed circuit for the semaphore arm of the first unit including a front neutral contact of said polarized relay and a normal polar contact of said polarized relay, and a circuit for the semaphore arm of said second unit including a front neutral and a normal polar contact both of said polarized relay as well as a front contact of said neutral relay.

5. In combination, a forward and a rear section of railway track, a polarized relay and a neutral relay for said forward section, means effective when the forward section is unoccupied to energize only said polarized relay in the reverse direction or only said polarized relay in the normal direction or both said relays according to traffic conditions in advance of said forward section, a pair of conductors for the rear section controlled by traffic conditions in that section, means effective to supply said conductors with energy of relatively low value in the reverse direction when said polarized relay is deenergized, means effective to supply said conductors with energy of said relatively high value in the reverse direction when said polarized relay only is energized in the reverse direction, and means effective to supply said conductors with energy of said relatively low value in the normal direction when said neutral relay is energized provided said polarized relay also is energized in the reverse direction.

6. A railway signal system comprising a stretch of track divided into sections, a track circuit including a track relay for each section, a pair of line conductors for each section each including a front contact of said track relay, means for each section for supplying the pair of conductors for the section next in rear with energy of a relatively low value in one direction or with energy of a relatively high value in said one direction or with energy of said relatively low value in the other direction in accordance with traffic conditions in advance, a polarized relay for each

section responsive to energy of either value receiving current from the associated conductors, a neutral relay for each section, means responsive only to energy of said high value and then only if said energy of high value is within predetermined maximum and minimum values also receiving current from the associated conductors for controlling said neutral relay, and traffic governing means for each section controlled by the associated neutral and polarized relays.

7. A railway signal system comprising a stretch of track divided into sections, a track circuit including a track relay for each section, a pair of line conductors for each section each including a front contact of said track relay, means for each section for supplying the pair of conductors for the section next in rear with energy of a relatively low value in one direction or with energy of a relatively high value in said one direction or with energy of said relatively low value in the other direction in accordance with traffic conditions in advance, a polarized relay for each section responsive to energy of either value receiving current from the associated conductors, a neutral relay for each section, means for each section responsive only to energy of said high value and then only if said energy of high value is within predetermined maximum and minimum values also receiving current from the associated conductors for governing the associated neutral relay, a signal for each section, means effective when only the polarized relay of a section is energized in said one direction to cause the associated signal to display a particular indication, means effective when the polarized relay of a section is energized in said one direction and said neutral relay also is energized to cause the associated signal to display a different indication, and means effective when only said polarized relay is energized in said other direction to cause the associated signal to display still a different indication.

8. In combination, a stretch of railway track divided into sections each provided with a track circuit including a track relay, a pair of conductors for each section each including a front contact of the associated track relay, means effective when one section is occupied to supply the conductors for the section next in rear of such occupied section with energy of a particular magnitude and direction, means then effective to supply the conductors for the section second in rear of such occupied section with energy of a different magnitude but in the same direction, means then effective to supply the conductors for the section third in rear of such occupied section with energy of said particular magnitude but in the other direction, and traffic governing means for each section selectively responsive to the direction and magnitude of the energy supplied to the associated conductors.

9. In combination, a forward and a rear section of railway track, a polarized relay and a neutral relay for said forward section, means effective when the forward section is unoccupied to energize only said polarized relay in the reverse direction or to energize said polarized relay in the reverse direction as well as said neutral relay or to energize only said polarized relay in the normal direction according to traffic conditions in advance of said forward section, a pair of conductors for the rear section controlled by traffic conditions in that section, a high voltage terminal

and a low voltage terminal, means effective to connect said conductors in one direction with said low voltage terminal when said polarized relay is deenergized, means effective to connect said conductors in the same direction with said high voltage terminal when said polarized relay only is energized in the reverse direction, and means effective to connect said conductors with said low voltage terminal in the other direction when said polarized relay only is energized in the normal direction or when said neutral relay is energized provided said polarized relay is also energized in the reverse direction.

10. In combination, a stretch of railway track divided into sections each provided with a track circuit including a track relay, a pair of conductors for each section each including a front contact of the associated track relay, means effective when one section is occupied to supply the conductors for the section next in rear of such occupied section with energy of a relatively low value in one direction, means then effective to supply the conductors for the section second in rear of such occupied section with energy of a relatively high value in said one direction, means then effective to supply the conductors for the section third in rear of such occupied section with energy of said relatively low value in the other direction, and signaling means for each section selectively responsive to the value and direction of energy supplied to the associated line conductors.

11. In combination, a section of railway track, a pair of conductors for said section, means for supplying said pair of conductors with current of a particular magnitude or with current of a different magnitude in accordance with traffic conditions in advance of said section, a first means responsive to energy of either magnitude receiving current from said pair of conductors, a second means responsive only to energy of said different magnitude and then only if the current of such different magnitude is within predetermined maximum and minimum values also receiving current from said pair of conductors, and traffic governing means for the section controlled by said first and second means.

12. In combination, a section of railway track, a pair of conductors for said section, means for supplying said pair of conductors with energy of a particular magnitude and direction or with energy of a different magnitude in the same direction, or with energy of said particular magnitude but in the other direction in accordance with traffic conditions in advance of said section, a polarized relay responsive to energy of either magnitude receiving energy from said conductors, a supply circuit, means controlled by a polar contact of said polarized relay for supplying current from said pair of conductors to said supply circuit, a relay responsive to the supply of current to said supply circuit and being operative only if the energy supplied thereto is within certain maximum and minimum values, whereby said relay is operated only when current of a particular polarity is supplied to said pair of conductors and then only if the magnitude of the current is within certain values, and traffic governing means for said section governed by said two relays.

GEORGE R. PFLASTERER.
